[57] CLAIM

The ornamental design for a credit card holder, as shown and described.

DESCRIPTION

FIG. 1 is a perspective view of a credit card holder, in a closed condition, showing my new design;

FIG. 2 is a perspective view thereof in an open condition;

FIG. 3 is a top plan view;

FIG. 4 is a bottom plan view;

FIG. 5 is a left side elevational view;

FIG. 6 is a right side elevational view;

FIG. 7 is a front elevational view;

FIG. 8 is a rear elevational view;

FIG. 9 is a perspective view of a credit card holder, in a closed condition, showing an alternate embodiment of my new design;

FIG. 10 is a perspective view thereof in an open condition;

FIG. 11 is a top plan view thereof;

FIG. 12 is a bottom plan view; thereof;

FIG. 13 is a left side elevational view thereof;

FIG. 14 is a right side elevational view thereof;

FIG. 15 is a front elevational view thereof;

FIG. 16 is a rear elevational view thereof; and

FIG. 17 is a fragmentary perspective detail view, to an enlarged scale, of the seams provided thereon, at the arrow XVII of FIG. 2.
